UNITED STATES PATENT OFFICE.

OLGA LOUISE ARLEN, OF NEW YORK, N. Y.

FACIAL BANDAGE.

Application filed November 5, 1926. Serial No. 146,381.

This invention relates to a facial bandage and has for its principal object to provide a construction which will very effectively restore the natural and youthful appearance to the wearer's face. This object I achieve by providing means for lifting the muscles of the face back into their normal position and supporting them in that position. Bandages have been devised hitherto with the object of removing double chins or the like but all of these devices known to me have failed to perform the desired function. This failure is due to the fact that the prior art bandages do not properly lift and support the muscles of the face. Instead of performing that function they tend to stretch the chin and cheek muscles backwardly from the chin along the lower jaw, the natural result being that the skin is drawn taut over the chin and lower jaw. That is, the action is a pulling one which, of course, is unnatural. As soon as the pulling force is released the muscles will then sag back to their former position. Furthermore, the pulling action tends to produce more looseness in the muscles and flesh by stretching them, and thus the trouble is made worse rather than being cured.

My invention will be better understood from an inspection of the accompanying drawings and, referring thereto:

Figure 1 is a full face view of my invention as applied to a person's head.

Figure 2 is a half face view of the same head.

Figures 3 and 4 are views in profile of a person's face illustrating the action of my invention.

The bandage forming my invention comprises a hood 1 which exemplifies a means for supporting the bandage on the head. It is to be understood that any other suitable form of support may be employed. The support terminates in a pair of depending flaps 2 and 3, one on either side, and each adapted to contact with a cheek and jaw of the wearer. Each flap is made of such a length that it will extend around the jaw past the mouth, the flap 2 terminating at 4 and the flap 3 terminating at 5. The end of each flap is provided with securing means and in this embodiment these securing means are shown as cords 6 and 7 secured respectively to the ends 4 and 5 of the flaps, by means of a plurality of cords 8 and 9. The cords 8 are passed through suitable aper-

tures 10 in the flap 3 so that the flap 2 may be disposed beneath the flap 3 and yet the cord 6 may be disposed on the exterior of the bandage. The two cords may be knotted together at 11 as plainly shown in Figure 2.

It has been my observation that facial deformities are caused to a very large extent if not entirely by sagging cheek and mouth muscles. The device as described above will adequately lift and support the cheek and mouth muscles and, to aid in supporting the mouth muscles, I provide a pair of aligned apertures 12 in the two flaps through which the lips of the wearer may be placed. These apertures are more than mere openings for the mouth, but are of a size and form to permit the lips to protrude therethrough, as will be explained later. This arrangement will support the mouth muscles because the lips will be pulled up and forwardly by the action of the two flaps. The natural, youthful position of the mouth muscles is one approaching a pout. That is, the lips of a child are much more prominent than those of an adult. When the mouth muscles begin to drop then they permit the chin muscles to sag with the result that a double chin is ultimately formed. This result is also hastened by the dropping of the cheek muscles.

In prior art devices known to me the muscles of the cheek have been drawn upwardly from the chin in an effort to remove the double chin effect. It will be noted that my device does not act in this way. For example, the flap 2 when drawn into position will merely lift the cheek muscles 13 on the right side of the face and also will lift the mouth muscles 14, causing them to protrude through the aperture 12. The entire action is a gentle supporting one instead of a violent stretching one as in prior art devices. In like manner the flap 3 will lift and support the cheek muscles 15 on the left cheek of the wearer and will also lift and support the mouth muscles which protrude through the aperture 12. As pointed out above these apertures are sufficiently large to permit the lips to protrude therethrough, and therefore form a support for the lips. The action of the flaps is to cause the lips to protrude and then the apertures form a support for the lips in their protracted position.

The action of my invention is illustrated in Figures 3 and 4. In Figure 3 is shown

a typical face of a middle-aged person in which the mouth has begun to drop and in which the mouth muscles 14 have sagged. At the same time the cheek muscles 15 have 5 also sagged and the result is an accumulation of flesh at 16 beneath the chin, this formation being generally referred to as a double chin. The action of a bandage constructed according to my invention is to lift 10 the mouth muscles 14 to the approximate position shown in Figure 4 and also to raise the cheek muscles as shown in that figure. The result is a change from the hollow appearance of Figure 3 to the plump appearance of Figure 4, the latter being the natural, youthful condition of the flesh of the face.

In order to help in maintaining the bandage in position each flap is provided with a portion extending under the jaw and fitting 20 the chin as indicated at 17. This portion, however, is not relied upon to affect the muscles or flesh of the chin. When the cheek and mouth muscles are lifted, the chin muscles will automatically be restored to 25 their natural position. Excessive flesh under the chin is caused by sagging of the cheek and mouth muscles and, therefore, when these are restored to their natural position it is not necessary to work upon the chin 30 muscles themselves.

It will be seen that the action of my device avoids the stretching of the flesh back over the chin and jaw as in prior art devices. The flesh is lifted vertically, which causes it 35 to protrude forwardly, rather than to stretch back toward the top of the head. The first position is natural while the second is unnatural.

My device is one which may be easily made 40 from any suitable material such as silk or some elastic material. It may be easily designed to fit heads of various shapes so as to avoid unnecessary discomfort. Discomfort is also avoided by the fact that the action of 45 the bandage is natural rather than unnatural.

I am aware that various changes in details of construction may be made without departing from the scope of my invention and therefore I do not intend to limit myself 50 except by the appended claims.

I claim:

1. A facial bandage comprising means to support the bandage on the head, two flaps adapted to engage the opposite cheeks of the 55 wearer, said flaps overlapping each other over the mouth, and means to secure said flaps in their overlapping position.

2. A facial bandage comprising means to

support the bandage on the head, two flaps adapted to engage the opposite cheeks of the 60 wearer, said flaps overlapping each other, and means to secure said flaps in their overlapping position, wherein they lift and support certain of the cheek and mouth muscles in their natural position.

3. A facial bandage comprising means to support the bandage on the head, two flaps adapted to engage the opposite cheeks of the 65 wearer, said flaps overlapping each other over the mouth, means to secure said flaps in their overlapping position wherein they lift and support certain of the cheek and mouth muscles, and means on said flaps to support the mouth muscles.

4. A facial bandage comprising means to support the bandage on the head, two flaps adapted to engage the opposite cheeks of the 70 wearer, said flaps overlapping each other over the mouth, and means to secure said flaps in their overlapping position wherein they lift and support certain of the cheek and mouth muscles, said flaps being provided with aligned apertures through which the lips of the wearer may protrude.

5. A facial bandage comprising means to support the bandage on the head, two flaps adapted to engage the opposite cheeks of the 75 wearer and to extend under the wearer's chin, said flaps overlapping, and means to secure said flaps in their overlapping position wherein they lift and support certain of the cheek and mouth muscles in their natural 80 position.

6. A facial bandage comprising means to support the bandage on the head, two flaps adapted to engage the opposite cheeks of the 85 wearer and to extend under the wearer's chin, said flaps overlapping, and means to secure said flaps in their overlapping position wherein they lift and support certain of the cheek and mouth muscles, said flaps being provided with aligned apertures through which the lips of the wearer may protrude.

7. A facial bandage comprising means to support the bandage on the head, two flaps adapted to engage the opposite cheeks of the 90 wearer, and means to secure each flap in position against a cheek, said means engaging the opposite flap, whereby certain of the 95 muscles of the cheek are lifted to their natural position without being stretched back from the chin.

In testimony whereof, I have affixed my signature to this specification.

OLGA LOUISE ARLEN.
